(57) **CLAIM**

The ornamental design for a drill chuck, as shown and described.

DESCRIPTION

FIG. 1 is a front view of a drill chuck showing my new design;

FIG. 2 is a right side view thereof;

FIG. 3 is a left side view thereof;

FIG. 4 is a rear view thereof;

FIG. 5 is bottom view thereof;

FIG. 6 is a top view thereof;

FIG. 7 is a first perspective view thereof; and,

FIG. 8 is a second perspective view thereof.

The broken line showing of portions of the drill chuck is for illustrative purposes only and forms no part of the claimed design.
